WRENCH

Stephen Uvaney, Cold Spring, N. Y.

Application May 18, 1936, Serial No. 80,297

3 Claims.

(Cl. 81—100)

This invention relates to improvements in wrenches (especially the Stilson type), particularly jaw-wrenches useful for manipulating long or heavy pipe.

5 One object of the invention is to provide two-jaw wrench formed to grip almost entirely around the circumference of a pipe, and in any event to grip at three or more areas simultaneously, thus affording a very extensive surface (or surfaces) 10 gripped by the wrench.

A second object of the invention is to provide at least one jaw of such a wrench with an inwardly-extending pipe-gripping portion, or continuation, shown as a depending bill in the accompanying drawing, in consequence of which arrangement the tool has, when in use, the extensive gripping surface (or surfaces) spoken of.

A third object of this invention is to provide 15 mutually cooperating parts all flexibly or articulately carried by a handle-member, to automatically grip around a pipe, or other object.

A fourth object of the invention is to provide a wrench having automatically-adjustable parts, as a consequence of which, because of the mere 20 sliding of the wrench, the latter automatically grips around various sizes of pipes and other objects.

A fifth object of the invention is to provide a wrench having several cooperating parts having 25 limited movements relatively one to the other, to the end that the wrench may have a ratchet action with respect to a pipe or other object.

A sixth object of the invention is to provide a wrench having novel constructions and combinations of parts.

A seventh object of the invention is to provide a form of wrench capable of gripping and turning a pipe very quickly, as compared with jaw wrenches heretofore in use.

40 The accompanying drawing illustrates one form of wrench which embodies my present improvements. As hereinafter mentioned, said improvements may be embodied in other forms of wrenches.

45 Figure 1 is a side view of a specific form of the wrench, with the jaws opened, to release or to grip a pipe, or other object. Fig. 2 is a like view, (parts being shown as being broken away, for clearness).

50 The figure shows, particularly, the relation of shape of the freely-movable jaw and parts. Fig. 3 is a rear view of the wrench, showing the relation of the jaw-parts, and looking from the right towards the left of Figure 1.

Figure 4 is a cross-section, through the line 4—4 of Fig. 2, and looking in the direction indicated by the arrows.

Figure 5 is a view in perspective of the movable jaw and the integral bifurcated shank.

Referring to Fig. 2, said figure illustrates the wrench as gripping around a pipe (dotted) and over a very large extent of the circumferential surface thereof.

A indicates the handle of the wrench. It is 10 shown as broken away in Figs. 2 and 3, to permit a more close grouping of the several figures.

B indicates a yoke, which has a tubular guide-opening, C, from top to bottom and through said yoke. The side members of the guide opening 15 are provided with short cross wise slots, as hereinafter mentioned. As illustrated, the handle and the tubular yoke, B, may be a single metal casting or forging. The handle-member also has a gripping part, shown in the drawing as an inserted and replaceable plate, D, of hard metal, 20 with a plurality of gripping teeth or ribs thereon, so as to be crosswise of the fixed member of the wrench when the latter is in use. The jaw D can conveniently be termed a fixed jaw, inasmuch as it performs its function in fixed position.

The handle-member of the wrench movably carries a gripping member combined therewith, and with novel parts, in such fashion that said gripping-member cooperates to automatically 30 grip around the exterior of a pipe (or other object). In addition to achieving such result, the special combination and arrangement of parts shown in the accompanying drawing, also grips

35 around the exterior of a pipe at more than two surface areas, that is at three or more considerable or large surfaces. Thus, inspection of Fig. 2 will show that the gripping ribs or teeth of the handle-member and those of the separately movable jaw grip around at least one-half of the entire circumference of a pipe (the latter being shown as a dotted circular figure).

In the illustrated specific embodiment of my invention, the movable wrench-jaw, E, is shown 40 as having two loosely connected portions, E and G, one of these (E) having a solid head, and being also bifurcated, or forked, as particularly shown in Figure 5. The free end of the auxiliary jaw G is integral with a slide, H, shown in Figs. 1 and 2 and slidably fits within the guide B, hereinbefore spoken of as being integral with the handle-member, A. The other (upper) end of the auxiliary jaw G is loosely connected between the upper ends of the legs F and F' of the forks,

45 by means of a bolt which passes through the 50 55

said upper end of auxiliary jaw G and also through openings O and O' across the movable jaw-part, E. A bolt, O², is used for the purpose, as shown in Fig. 2, and also passes through a slot, P, in the upper end of the auxiliary jaw, G, with the result that the auxiliary jaw G moves not only around the axis of the bolt but may also swing away from the same for a small distance.

10 As before stated, the movable jaw, E, is formed to provide the forks F and F'. These forks are each slotted, longitudinally, as shown at J and J'.

The forks (F and F') straddle, and fit at opposite sides of the yoke, B, previously mentioned.

15 They are held in slidable relation with said guide-frame and also in their own operative relation, by means of connections, particularly shown in Figs. 1, 2 and 4, and which employ short bolts M and M' which pass through short slots, K and K', through and crosswise of the yoke, B, and which also pass through the long slots, J and J', of the forks, F and F', serving as guides for said forks during the closing and the opening of the jaws of the wrench.

25 As shown in Figs. 1-3, the rear face, or edge, of the slide, H, is provided with a rack, X, the teeth thereof being disposed to be engaged by the tooth of a pawl, Y, operable to unlocking position by the user's finger, and to the locking position by a spring, Z.

Particular attention is called to the form of the movable jaw E and the auxiliary jaw G especially shown in Figs. 1, 2 and 5, the novel and highly-efficient feature being that the forward end of the jaw E is provided with an extension (bill, neb or the like) which in use tends to overhang the jaw D of the handle-member. The overhanging or extending portion, identified as E', of the jaw E as well as the under surface of the member G are both provided with gripping teeth or ribs, E², and these cooperate with each other, and also with the gripping means of the fixed jaw D, to grip around three or more surface areas of a pipe, holding the same firmly, when desired, over one-half or more of the circumference of the pipe.

The manner of assembling the parts of the illustrated wrench will be obvious to any person skilled in the operation and construction of wrenches.

pushed towards extreme position (that shown in Fig. 1). The wrench jaws are then caused to engage over a pipe, and the jaws are closed, so that, as shown in Fig. 2, the pipe is almost surrounded by the jaws, and one-half (or more) of the pipe's circumference may be grippingly engaged upon the rocking movements of the wrench. 5

What I claim is;

1. A wrench comprising a handle, a yoke integral with said handle, a fixed jaw on the upper end of said handle, a movable jaw having an integral bifurcated shank, an auxiliary jaw having an integrally secured shank, said auxiliary jaw being pivotally mounted within the movable jaw shank, said movable jaw shank slidably embracing said yoke and pivoted thereto, said auxiliary jaw shank being slidably mounted within said yoke with limited lateral movement therein; and rack and pawl means to adjustably position said jaws, said rack and pawl being disposed between said auxiliary jaw shank and said yoke. 10 15 20

2. A wrench comprising a handle, a yoke integral with said handle, a fixed jaw on the upper end of said handle, a movable jaw having an integral bifurcated shank, an auxiliary jaw having an integrally secured shank, said auxiliary jaw being pivotally mounted within the movable jaw shank, said movable jaw shank slidably embracing said yoke and pivoted thereto, said auxiliary jaw shank being slidably mounted within said yoke with limited lateral movement therein; a rack disposed on said auxiliary shank, and a spring-biased pawl carried by said yoke. 25 30

3. A wrench comprising a handle, a yoke integral with said handle, a fixed jaw on the upper end of said handle, a movable jaw having an integral bifurcated shank, an auxiliary jaw having an integrally secured shank, said auxiliary jaw being pivotally mounted within the movable jaw shank, said movable jaw shank being provided with longitudinal slots in each of the forks thereof, said yoke having outstanding lugs on either side thereof adapted to engage the longitudinal slots in the shank of said movable jaw; said auxiliary jaw shank being slidably mounted within said yoke with limited lateral movement therein; and rack and pawl means to adjustably position said jaws, said rack and pawl being disposed between said auxiliary jaw shank and said yoke.

STEPHEN UVANEY.
